SECONDARY ALKYL SULPHATES AS WASHING AND EMULSIFYING AGENTS

Jacob N. Wickert, Charleston, W. Va., assignor, by
mesne assignments, to Union Carbide and Car-
bon Corporation, a corporation of New York

No Drawing. Application January 10, 1935,
Serial No. 1,172

8 Claims. (Cl. 87—5)

This invention relates to washing and emulsi-
fying operations; and more especially it con-
cerns the utilization therein of water-soluble in-
organic salts, and amine or substituted amine
5 salts, of the half esters of sulphuric acid with
saturated secondary branched-chain alcohols
having at least 8 carbon atoms in the molecule.
The invention is of special utility in the prepara-
tion and use of liquors employed in the treat-
10 ment of textiles and fibrous substances, such as
in wool scouring, and in the washing of cotton,
wool, and silk textiles.

Heretofore, there have been employed as deter-
gents certain half sulphuric esters of primary
15 alcohols or amines containing straight chains of
10 to 20 and more carbon atoms, and derived
from the soap-forming fatty acids.

The present invention is based in important
part upon the discovery that salts of mono-
20 esters of sulphuric acid derived from saturated
secondary branched-chain alcohols having 8 or
more carbon atoms in the molecule are highly
efficient cleansing agents and emulsificants, either
when used alone, or with other detergents such
25 as soap and sodium carbonate, in solutions in
water or the usual volatile solvents.

The alkali metal salts and substituted amine
salts of the half esters of sulphuric acid with sec-
ondary branched-chain aliphatic alcohols having
30 8 or more carbon atoms in the molecule possess
in common strong detergent and emulsifying
properties well adapting them for use in the pre-
paration of cleaning, scouring, and emulsifying
compositions. However, those derived, in the
35 manner hereinafter indicated, from secondary
aliphatic alcohols having 14 or more carbon
atoms in the molecule are especially effective in
cleaning and washing operations conducted un-
der neutral or alkaline conditions, reducing
40 greatly the interfacial tension between the wash-
ing fluid and any oily or other materials present
in the material to be cleaned.

These sulphate esters of the higher secondary
aliphatic alcohols exist as colorless, amorphous
45 waxes, completely soluble in organic solvents
such as alcohols, esters, ketones, and hydrocar-
bons; and they are much more soluble in water
than are sulphuric acid esters of corresponding
carbon content, derived from primary alcohols or
50 those having straight carbon chains.

Those sulphate esters of the invention having
less than 15 carbon atoms in the molecule are
completely soluble in water, yielding a clear solu-
tion at 0.25% concentration at room temperature.

55 Those having 15 or more carbon atoms in the

molecule form faintly cloudy solutions which
do not settle out upon standing; whereas soaps
and other detergent solutions under similar con-
ditions of concentration are very cloudy, and in
many instances precipitate a solid after several 5
days.

These new sulphate esters yield voluminous
foams when shaken with warm water. The cal-
cium and magnesium salts present in moderately
hard waters are not precipitated by these com-
pounds in dilute solutions, since their calcium 10
and magnesium salts are almost as soluble as
the sodium salts. Dilute aqueous solutions of
the alkali metal sulphate esters when slightly
acidified still retain a large proportion of their 15
detergent properties. Such solutions evidently
contain some alkyl hydrogen sulphate.

The neutral secondary alkyl sulphates of the
present invention may be produced by condens-
ing an aliphatic primary or secondary aldehyde 20
having at least 4 carbon atoms in its molecule,
with acetone, methylethyl ketone, or a ketone
derivative of either, in the presence of an alka-
line catalyst. By the term "secondary aldehyde" 25
is meant an aldehyde in which the carbon atom
connected with the aldehyde group is also directly
connected with 2, and only 2, other carbon
atoms.

The resultant reaction mixture is made slight-
ly acid to phenolphthalein by means of a suit-
able acid, and the acidified mixture is heated 30
to its boiling point, thus converting the ketol pres-
ent as a result of the condensation of the alde-
hyde and ketone, into an unsaturated ketone.
The mixture is fractionally distilled under vac-
uum to separate the unreacted starting mate-
rials and water from the ketone; and to isolate 35
the ketone from the said mixture. This ketone
is hydrogenated under superatmospheric pres-
sure, preferably around 800-1000 pounds per 40
square inch, and at temperatures up to around
150° C., in the presence of a hydrogenation cata-
lyst such as active nickel. The saturated sec-
ondary alcohol thus formed is then recovered by 45
fractional distillation of the reaction mixture
under vacuum, and is converted to its acid sul-
phate by any of the usual sulphating methods.
According to one method, the secondary alcohol
is reacted with approximately an equivalent
amount of equimolar proportions of 96% sul-
phuric acid and acetic anhydride, at low tem-
peratures maintained preferably from around 50
0° to around 10° C. The concentration of the
sulphuric acid can vary considerably; or this
acid or sulphuric anhydride can be used alone; 55

and other anhydrides of organic acids, or the acids themselves, or their chlorides, may be substituted for the acetic anhydride; or chlorosulphonic acid dissolved in a suitable diluent such as $\beta\beta'$ dichlorethyl ether effectively may be reacted with a solution of the secondary alcohol in the same or other solvent.

The acid alkyl sulphate thus produced is neutralized, preferably with a caustic alkali or ammonia, or an organic amine such as one of the ethanolamines. This yields the corresponding salt of the alkyl sulphate.

Among the alkyl sulphates of secondary branched-chain alcohols found highly effective as detergents in the washing of textiles and other materials soiled with grease, paint, carbon, and other objectionable substances, are those listed in Table I.

Table I

Substance	Apparent formula of intermediate alcohol	Number of carbon atoms
1. Sodium octyl sulphate	3, methylheptanol-2	8
2. Sodium nonyl sulphate	3, ethylheptanol-6	9
3. Sodium decyl sulphate	2methylnonanol-4	10
4. Sodium undecyl sulphate	5methylnonanol-2	11
5. Sodium dodecyl sulphate	3, ethyl-3-methylnonanol-6	12
6. Sodium tridecyl sulphate	3, ethylundecanol-6	13
7. Sodium tetradecyl sulphate	7, ethyl-2-methylundecanol-4	14
8. Sodium pentadecyl sulphate	3,9 diethylundecanol-6	15
9. Sodium pentadecyl sulphate	5,ethyltridecanol-8	15
10. Sodium hexadecyl sulphate	9, ethyl-5-methyltridecanol-6	16
11. Sodium heptadecyl sulphate	3,9 diethyltridecanol-6	17
12. Sodium nonadecyl sulphate	5,11 diethylpentadecanol-8	19
13. *M.E.A. tetradecyl sulphate	7, ethyl-2-methylundecanol-4	16
14. *M.E.A. heptadecyl sulphate	3,9 diethyltridecanol-6	19
15. *M.E.A. nonadecyl sulphate	5,11 diethylpentadecanol-8	21
16. **T.E.A. tetradecyl sulphate	7, ethyl-2-methylundecanol-4	20
17. **T.E.A. heptadecyl sulphate	3,9 diethyltridecanol-6	23
18. **T.E.A. nonadecyl sulphate	5,11 diethylpentadecanol-8	25

*M.E.A. designates monoethanolamine.

**T.E.A. designates triethanolamine.

Table II

Numbers corres. to substance	0.25% aqueous solution	
	Drop number at 30° C.	Interfacial tension dynes per cm. at 26° C.
1	30	37.8
2	32	32.9

4	38	24.7
5	42	24.0
6	60	16.6
7	129	7.0
8	114	6.0
9	167	11.0
10	228	3.5
11	516	2.3
12	3250	0.46
13	600	8.6
14	7270	1.1
15	4040	0.46
16	1075	6.0
17	6190	0.58
18	4390	0.57
Water	22	43.3

It will be noted upon reference to Table I that the higher molecular-weight members of the alkyl sulphates employed in the present invention generally possess at least one alkyl side-chain directly connected with the third carbon

atom of the main chain spaced from that carbon atom to which the sulphate group is attached; and that many of the alkyl sulphates have two branched-chain alkyl groups respectively connected directly to the carbon atom to which the sulphate group is attached. These structural characteristics possessed by so many compounds of this class examined appear to have an important bearing on the efficiency of such compounds as detergents and emulsifying agents in the compositions employed.

The power of depressing the interfacial tension between water and hydrocarbons is one of the properties possessed to a remarkable degree by the sulphate esters of secondary branched-chain alcohols of the invention. Evaluation of this power may be obtained by drop number measurements. Those recorded in Table I consist in counting the number of drops formed by a plane-ground capillary tip when a fixed volume (10 c. c.) of an aqueous solution containing .25% by weight of the sample is allowed to flow slowly into a body of kerosene maintained at 30° C. The tip is of such size that the fixed volume of water, selected as a standard, will be divided into about 25 drops. The rate of flow is so regulated that the drops will form distinctly and can be counted conveniently. The number of drops observed may vary somewhat from one sample to another, particularly when the number is in excess of 100. Therefore, the values here recorded are in some cases the average of those found for several samples. This depressing power is measured directly by the number of drops formed. It is closely related to the detergent power, and particularly to the emulsifying power, of the sample.

Reference to the table will show the greatly increased effectiveness of the neutral alkyl sulphates having 14 or more carbon atoms in their molecules over those of lower molecular weight for depressing the interfacial tension between aqueous solutions and hydrocarbons.

The following examples will serve to illustrate the invention:

Example 1

A soiled white silk cloth impregnated with carbon black, mineral oil, manganese dioxide, and carbon tetrachloride, was agitated for five minutes in a .25% aqueous solution of sodium nonadecyl sulphate (see Table I). The cloth was then rinsed with water and dried. Practically all of the color imparted by the impurities was removed in the washing, and the white color of the cloth restored. Similarly, the mono- and triethanolamine heptadecyl and nonadecyl sulphates were highly effective detergents in washing silk.

Example 2

A soiled white cotton cloth stained with mineral oil, carbon black, and manganese compounds, was treated with an aqueous solution of sodium heptadecyl sulphate, following the procedure described in Example 1. After rinsing the washed cloth in water and drying it, the color imparted by the impregnating materials had been in main part eliminated.

Unboiled cotton yarn was soaked in a dilute aqueous solution of the sodium nonadecyl sulphate, and when dried was very appreciably whiter and softer, indicating a strong cleaning action.

The higher members of the series of sulphate esters, those having 14 or more carbon atoms in the molecules, have a detergent power supe-

rior to the lower members of the series; although it has been discovered that blends of the compounds of higher carbon content than 14 carbon atoms with those of lower carbon content are efficient cleansers in certain instances, and have better hard water and sea water solubility than those of the higher carbon content alone. Blends of one or more of these sulphate esters with ordinary soaps also are good detergents.

10 Hands soiled with grease, fresh paint, and other forms of dirt readily are washed clean with water containing any of the sulphate esters of the invention. A copious lather is obtained, and the soil is removed as completely and efficiently as 15 with special pumice-base soaps and others.

Textiles readily may be washed clean in aqueous or solvent solutions containing hardness-imparting ingredients or acidic substances, by the employment of a small amount of the sulphate esters of one of the secondary alcohols produced in the manner herein described. Voluminous suds or froth which are relatively stable are formed upon shaking dilute solutions of these sulphate esters. For example, upon agitating a .25% aqueous solution of the sodium tetradecyl sulphate, or of the corresponding mono- or triethanolamine salt thereof, in hard water containing 400 parts per million of CaCl_2 , a voluminous foam is produced which has over 15 times the volume of 20 the foam produced under similar conditions using a sulphation product now on the market for the purpose and made from technical oleyl alcohols. Moreover, whereas the foam produced by the said sulphate esters of the present invention 25 persisted for over two hours after agitation had ceased, the foam produced by the oleyl alcohol derivatives lasted but six seconds.

When sea water was substituted for the hard water mentioned above, the tetradecyl sulphates of this invention gave foams which persisted for 40 over two hours, whereas the oleyl alcohol derivatives produced but from one-third to one-half as much foam, which vanished in eight seconds after discontinuing the agitation.

45 The invention is susceptible of modification within the scope of the appended claims:

I claim:

1. In the process of washing textiles, the step which comprises agitating the same while immersed in a solution of a neutral water-soluble 50 salt of a sulphuric acid ester derived from a saturated secondary branched-chain monohydric aliphatic alcohol, and having at least 14 carbon atoms in its molecular structure.

55 2. The process for cleaning textile materials,

which comprises contacting the said materials with an aqueous solution having therein a water-soluble salt of an acid sulphuric ester of a saturated secondary branched-chain monohydric aliphatic alcohol having at least 14 carbon atoms 5 in its molecular structure.

3. A detergent and emulsifying composition, which comprises a solution of a water-soluble sulphuric acid ester of a saturated secondary branched-chain monohydric aliphatic alcohol 10 containing at least 8 carbon atoms in its molecule and having two branched-chain alkyl groups respectively connected directly to the carbon atom to which the sulphuric acid group is attached.

15 4. A detergent and emulsifying composition, which comprises a solution of a water-soluble salt of a sulphuric acid ester of a secondary branched-chain monohydric aliphatic alcohol containing at least 14 carbon atoms in its mole- 20

25 5. A detergent and emulsifying composition, which comprises a solution of a water-soluble salt of a sulphuric acid ester of a secondary branched-chain monohydric aliphatic alcohol containing 25 from 14 to 19 carbon atoms in its molecule.

6. A detergent composition comprising a solution of a water soluble sulphate ester of a saturated secondary branched-chain monohydric aliphatic alcohol, which ester has at least 8 carbon atoms 30 in its molecule and has at least one alkyl side-chain directly connected with the third carbon atom of the main chain spaced from that carbon atom to which the sulphate group is attached.

35 7. In the process of washing textiles, the step which comprises contacting the same with a solution of a water-soluble sulphate ester of a saturated secondary branched-chain monohydric aliphatic alcohol having at least 8 carbon atoms 40 in its molecule and having two branched-chain alkyl groups respectively connected directly to the carbon atom to which the sulphate group is attached.

45 8. In the process of washing textiles, the step which comprises contacting the said materials with a solution of a water-soluble sulphate ester of a saturated secondary branched-chain monohydric aliphatic alcohol having at least 8 carbon atoms 50 in its molecule and having at least one alkyl side-chain directly connected with the third carbon atom of the main chain spaced from that carbon atom to which the sulphate group is attached.
